BRACELET BUCKLE

Eugen Prestinari, Summit, N. J., assignor to
Gemex Company, a corporation of New Jersey

Application September 21, 1932, Serial No. 634,115

8 Claims. (Cl. 24—71)

This invention relates to a bracelet buckle extension device and has for one of its objects the provision of a construction which may be relatively simple and inexpensive to manufacture and yet one which will house in a compact space and have an attractive appearance when worn in a bracelet such as is particularly used for securing a wrist watch in position.

Another object of the invention is the provision of an extension device which may be adjusted when in folded position to contract the encircling size of the bracelet in which it is secured by simple pressure upon parts thereof tending to move the same to this contracted position.

A further object of the invention is the provision of a construction which by certain other manipulations may be permitted to expand and be adjusted while on the wrist of the wearer to enlarge the encircling size of the bracelet by the operation of a controlling member for such purposes.

With these and other objects in view, the invention consists of certain novel features of construction, as will be more fully described, and particularly pointed out in the appended claims.

In the accompanying drawing:

Fig. 1 is a perspective view of an extension device in folded contracted position.

Fig. 2 is a similar view showing the sliding link member positioned in extended position.

Fig. 3 is a perspective view showing the parts in unfolded and extended position that the largest encircling length may be had for the bracelet in which it is connected.

Fig. 4 is a bottom view of two of the sections in unfolded position.

Fig. 5 is a sectional view thru the channel section and illustrating the sliding link member therein with one of its teeth in connection with the catch device in which it slides.

Fig. 6 is a central sectional view thru the device in folded position.

Fig. 7 is a perspective view of the sliding link member alone.

It is found desirable in the use of extension devices to provide one in which there is an expanding action both by unfolding and by sliding the parts one on the other in a relation such that the slideable part is used for the last stages of more minute adjustment after the device is folded into position on the wrist of the wearer, and in order that such a construction may be formed in a compact manner and one which will be comfortable upon the wrist, I have provided a plate 55 which is slideable in one end section of the fold-

able construction which has formed integral therewith an arm having ratchet teeth permitting the same to be slid in one direction and then held in the position to which it is moved and yet one whereby the integral toothed arm may be flexed to permit of sliding adjustment; and the following is a detailed description of the present embodiment of this invention illustrating the preferred means by which these advantageous results may be accomplished:

With reference to the drawing, the foldable sections are designated generally 11 and 12 and are hinged together as at 14, thence hingedly connected as at 13 to a housing link 10 to permit them to fall one upon the other within the housing link 10 which is formed generally channel shaped and has a top wall 15 and side walls 16. This section 11 is of such a dimension as to permit it to be received within the channel section 12 and the end upon which the pivot 13 is provided is T-shaped as at 21 to space the section 11 from the side walls 16 permitting the side walls 20 of the section 12 to fit therebetween. One of the side walls 16 is slotted as at 17, while both of the side walls are provided with recesses on their inner surfaces 18 to receive the projections 19 on the side walls 20 of the section 12 to hold the sections in folded position.

The sliding adjustment is accomplished by the provision of a sliding link member designated 22 which is fitted to slide along the top wall 15 of the housing link 10 and between this top wall and the folded sections 11 and 12 when in a position to house within the housing link 10. Sliding link 22 is of plate like formation being 30 all in a substantially single plane and is slotted as at 23 to provide a resilient arm 24 for the ratchet teeth 25 along one edge thereof and a finger piece 26 folded from the end of this arm to extend outwardly thru the slot 17 in the side wall 16.

A pawl member 27 is provided on the housing link 10 by folding inwardly a portion of the stock cut from the slot 17, which pawl engages any selected one of the teeth 25 of the arm 24. These teeth are inclined such that upon pressure inwardly of the member 22, the arm will flex inwardly permitting the same to slide from one tooth to another and be held against outward movement in the opposite direction by reason of the more abrupt shape of the teeth formed on this arm. If, however, it is desired to move the member outwardly pressure is applied to the finger piece 26 by moving the arm inwardly disengaging it from the pawl 27 and permitting free outwardly movement of the sliding link 22.

The movement of the sliding link 22 is independent of the folded or unfolded position of sections 11 and 12 and adjustment may be accomplished in either direction regardless of whether the sections are housed within the housing link 10 or extended therefrom, as shown in Fig. 3. Movement of the sliding link 22, however, is limited by reason of the finger piece engaging either of the ends 29 or 30 of the slot 17 in the side wall and thus the parts are held in the desired assembled relation without danger of being accidentally disengaged.

This buckle may be attached to a bracelet by securing the same thereto thru the opening 31 in the sliding link 22 and thru the opening 32 in the section 12, that suitable flexible connection may be had between the parts.

The foregoing description is directed solely towards the construction illustrated, but I desire it to be understood that I reserve the privilege of resorting to all the mechanical changes to which the device is susceptible, the invention being defined and limited only by the terms of the appended claims.

25 I claim:

1. In a bracelet extension buckle having a plurality of sections hinged together to fold one on the other, a section provided with a slot, a plate member slidable in said slotted section and 30 cut out to form an integral resilient arm along one side, notches on said arm, a detent on said section folded from the edge of said slot to be engaged by the selected notch in said arm, and an integral finger piece on the end of said resilient 35 arm and extending outwardly thru said slot to control said resilient arm.

2. In a bracelet extension buckle, in combination, a housing link member having a top and right angle flanges forming longitudinal side 40 walls, a sliding link slideable on and resting against the under side of the top of said housing link member and between said side walls, the thickness of said sliding link being less than the height of said walls to leave portions of the opposing 45 surfaces of said side walls exposed, one of said side walls having a longitudinal slot formed therein, an arm member secured to said sliding link, a plurality of ratchet teeth formed along one of said members, a pawl secured to the other 50 of said members and normally in engagement with said ratchet teeth, a fingerpiece secured to said arm member and extending through said slot, a plurality of link parts hingedly connected to each other, one of said link parts being hinged to one end of said housing link member, said link parts being shaped to fold into a nested position 55 within said housing link member below said sliding link so that the edges of the link part which is furthest from said housing link member when said link parts are unfolded are in engagement with said exposed portions of said side walls below said sliding link, whereby said teeth and said pawl may be disengaged to allow free sliding movement of said sliding link in contracting or extending 60 directions regardless of the position of said link parts with respect to said housing link member.

65 3. In a bracelet extension buckle, in combination, a housing link member having a top and right angle flanges forming longitudinal side walls, a sliding link resting against the under 70 side of the top of said housing link member and

75 between said side walls, the thickness of said sliding link being less than the height of said walls to leave portions of the opposing surfaces of said side walls exposed, one of said side walls having a longitudinal slot formed therein, an arm member secured to said sliding link, a plurality of ratchet teeth formed along one of said members, a pawl secured to the other of said members in engagement with said ratchet teeth, a fingerpiece secured to said arm member and extending through said slot, and a plurality of link parts hingedly connected to each other, one of said link parts being hinged to one end of said housing link member, said link parts being shaped to fold into a nested position within said housing link member below said sliding link, the link part which is furthest from said housing link member when said link parts are unfolded having right angle flanges along its longitudinal edges, the distance between the outer surfaces of said flanges and the inner surfaces of said side wall being substantially equal so that said exposed portions of said side walls and said flanges are in engagement when said link parts are in said nested position whereby said teeth and said pawl 25 may be disengaged to allow free sliding movement of said sliding link in contracting or extending directions regardless of the position of said link parts with respect to said housing link member.

30 4. In a bracelet extension buckle, in combination, a housing link member having a top and right angle flanges forming longitudinal side walls, a sliding link slideable on and resting against the under side of the top of said housing 35 link member and between said side walls, the thickness of said sliding link being less than the height of said walls to leave portions of the opposing surfaces of said side walls exposed, one of said side walls having a longitudinal slot formed therein, an arm member secured to said sliding link, a plurality of ratchet teeth formed along one of said members, a pawl secured to the other of said members and normally in engagement with said ratchet teeth, a fingerpiece secured to said arm member and extending through said slot, a plurality of link parts hingedly connected to each other, one of said link parts being hinged to one end of said housing link member, said link parts being shaped to fold into a nested position within said housing link member below said sliding link, the distance between the longitudinal edges of the link part which is furthest from said housing link member when said link parts are unfolded being substantially 50 equal to the distance between said exposed surfaces of said side walls so that said edges and said exposed surfaces are in engagement when said link parts are in said nested position, whereby said teeth and said pawl member may be disengaged to allow free sliding movement of said sliding link in contracting or extending directions regardless of the position of said link parts with respect to said housing link member.

55 5. In a bracelet extension buckle, in combination, a housing link member having a top and right angle flanges forming longitudinal side walls, a sliding link slideable on and resting against the under side of the top of said housing link member and between said side walls, the thickness 70 of said sliding link being less than the height of said walls to leave portions of the opposing surfaces of said side walls exposed, one of said side walls having a longitudinal slot formed therein, an arm member secured to said sliding link, 75

- a plurality of ratchet teeth formed along one of said members, a pawl secured to the other of said members and normally in engagement with said ratchet teeth, said teeth extending in a plane substantially parallel to said top of said housing link member, a fingerpiece secured to said arm member and extending through said slot, a plurality of link parts hingedly connected to each other, one of said link parts being hinged to 5 one end of said housing link member, said link parts being shaped to fold into a nested position within said housing link member below said sliding link, the distance between the longitudinal edges of the link part which is furthest from 10 said housing link member when said link parts are unfolded being substantially equal to the distance between said exposed surfaces of said side walls so that said edges and said exposed surfaces are in engagement when said link parts 15 are in said nested position, whereby said teeth and said pawl member may be disengaged to allow free sliding movement of said sliding link in contracting or extending directions regardless of the position of said link parts with respect to 20 said housing link member.
- 25 6. In a bracelet extension buckle having a plurality of link parts hinged together to fold one on the other, in combination, a housing member having top and longitudinal walls along its sides, a sliding link member slideable on and resting upon the under side of the top of said housing member between said walls and shaped to slide into extended and contracted positions with respect to said housing member, a plurality of ratchet teeth formed along a portion of one of said members, a catch portion on the other of said members and positioned to engage said teeth, one of said portions being movable in lateral directions with respect to the buckle and having a section facing the inside face of one of said walls, the extremities of said teeth and said catch portion being disposed between said section and said inside face of said last-mentioned wall so that movement of said movable portion away from said last-mentioned wall disengages said teeth and said catch portion, and a fingerpiece connected to said movable portion and extending laterally through said last-mentioned wall to a point spaced from the exterior of said last-mentioned wall whereby pressure upon said fingerpiece disengages said teeth and said catch portion to allow free sliding movement of said sliding link in extending and contracting directions.
- 30 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795
7. In a bracelet extension buckle having a plurality of link parts hinged together to fold one on the other, in combination, a housing member having top and longitudinal walls along its sides, a sliding link member slideable on and resting upon the under side of the top of said housing member between said walls and shaped to slide into extended and contracted positions with re-
- spect to said housing member, a plurality of ratchet teeth formed along a portion of one of said members, a catch portion on the other of said members and positioned to engage said teeth, said teeth and said catch portion being shaped to permit movement of said sliding link member in a contracting direction and prevent movement thereof in an extending direction when said teeth and said catch portion are in engagement, one of said portions being movable in lateral directions with respect to the buckle and having a section facing the inside face of one of said walls, the extremities of said teeth and said catch portion being disposed between said section and said inside face of said last-mentioned wall so that movement of said movable portion away from said last-mentioned wall disengages said teeth and said catch portion, and a fingerpiece connected to said movable portion and extending laterally through said last-mentioned wall to a point spaced from the exterior of said last-mentioned wall whereby pressure upon said fingerpiece disengages said teeth and said catch portion to allow free sliding movement of said sliding link in extending and contracting directions.
8. In a bracelet extension buckle, in combination, a housing link member having a top and longitudinal side walls, a sliding link member resting against the under side of the top of said housing link member and between said side walls and shaped to slide into extended and contracted positions with respect to said housing link member, the thickness of said housing link member being less than the height of said side walls to leave portions of the opposing surfaces of said side walls exposed, a plurality of ratchet teeth formed along a portion of one of said members and extending in a plane substantially parallel to said top, a catch portion on the other of said members positioned to engage said teeth, one of said portions being movable in lateral directions with respect to the top of said housing link member, a plurality of link parts hingedly connected to each other, one of said link parts being hinged to one end of said housing link member, said link parts being shaped to fold into a nested position within said housing link member so that the edges of the link part which is furthest from said housing link member when said link parts are unfolded are in engagement with said exposed surfaces of said side walls, said last-mentioned link part forming a bottom for said housing link member so that said teeth and said catch portion are enclosed by said top of said housing link member, said side walls and said last-mentioned link part, catch means disposed between the edges of said last-mentioned link part and said side walls, and a fingerpiece connected to said movable portion and extending through one of said side walls.

EUGEN PRESTINARI.
